UNITED STATES PATENT OFFICE.

FRANK ALLEN, OF NEW YORK, N. Y., ASSIGNOR TO THE ALLEN ICE MACHINE COMPANY, OF SAME PLACE.

ART OF MANUFACTURING TEMPERATURE-EQUALIZING COILS.

SPECIFICATION forming part of Letters Patent No. 644,841, dated March 6, 1900.

Application filed November 16, 1899. Serial No. 737,165. (No model.)

To all whom it may concern:

Be it known that I, FRANK ALLEN, a citizen of the United States, residing at New York, in the borough of Brooklyn and State of New York, have invented certain new and useful Improvements in the Art of Manufacturing Temperature-Equalizing Coils, of which the following is a specification.

This invention relates to the art of manufacturing temperature-equalizing coils for heating or cooling purposes generally and which are especially applicable to ammonia and other refrigerating machines.

The object of the invention is to produce such coils of the desired size quickly, conveniently, and inexpensively.

The invention consists of certain successive steps to be hereinafter described and then claimed.

In the accompanying drawings, Figure 1 is an elevation of a straight metallic tube which is adapted to form the inner coil of the article to be made. Fig. 2 is an elevation of a helically-coiled wire which is to be placed over said tube. Fig. 3 is an elevation of said tube wound with said wire. Fig. 4 is an elevation showing a straight outer tube placed over the said parts, part of the outer tube being broken away, so as to show the parts inside. Fig. 5 is an elevation of a temperature-equalizing coil made after my method, part of the outer tube being broken away; and Fig. 6 is an enlarged transverse section of one length of the coil.

Similar letters of reference indicate corresponding parts.

Referring to Fig. 5, the temperature-equalizing coil is shown to consist of an interior tube *a*, a helically-wound wire *b*, wrapped or placed around the same, and an exterior tube *c*, fitting snugly over the wire-wound tube *a*, this construction being carried out throughout the sinuosities of the coil and from end to end, the inner tube extending at both ends beyond the outer tube, so that the well-known headers (shown in dotted lines) may be applied without communicating with the inner tube.

In making the described temperature-equalizing coil a straight length of tubing *a*, Fig. 1, is cut off to the required length. A

wire *b*, Fig. 2, is now cut to such a length as will permit its being wound around the tube in the proportion of about one convolution to each lineal foot of the tube *a*, as shown in Fig. 3. Of course the wire may be previously wound in helical shape, as shown in Fig. 2, and then placed over the tube *a*. A larger piece of straight tubing *c*, Fig. 4, is now provided and the same placed over the wire-wound tube *a*. The wire should be of such thickness that it corresponds to one-half the difference between the internal diameter of the outer tube *c* and the external diameter of the inner tube *a*, or approximately so, so that the tubes can be placed over one another, with the wire serving as a separating medium, affording a neat fit and practically maintaining the concentricity of the tubes. The exterior tube *c* is made of somewhat less length than the inner tube, so that the said inner tube extends at both ends beyond the exterior tube. A suitable bending-machine is now used for the purpose of bending the assembled parts, causing them to assume the shape shown in Fig. 5, with alternate bends *a'* at the ends of the straight portions. Before bending the tubes and inclosed spacing-wire the portions to be bent are sufficiently heated to soften them, for if bent cold they will crack or break. The headers shown in dotted lines are then attached. In the case of forming a coil of helical shape the tubes are bent into such shape by means of a different bending-machine. Any of the machines on the market adapted for bending tubing may of course be used.

The advantage incident to this method of building up and forming a temperature-equalizing coil is that the separating-wire *b* serves as an interposed mandrel or anvil medium to preserve the concentricity of the tubes throughout their bends or sinuosities, as absolutely no collapsing or shifting of the tubes one against the other can take place, resulting, therefore, in a temperature-equalizing coil without joints and which at the same time is very simple and easily made at a slight cost of manufacture.

Having thus described my invention, what I claim as new, and desire to secure by Letters Patent, is—

1. The art of manufacturing temperature-equalizing coils having spaced interior and exterior tubes, the same consisting in interposing a helical spacing-wire between the tubes, and thereby forming a passage between the tubes, and then bending the said parts one on the other so as to form a coil, substantially as set forth.

2. The art of manufacturing temperature-equalizing coils having spaced interior and exterior tubes, the same consisting in the following steps, namely; placing a helically-wound wire around a tube, inclosing said

tube and wire within another tube, then heating the parts of the tubes to be bent, and finally bending the said parts at their heated portions, so as to form the sinuosities of the coil, substantially as set forth.

In testimony that I claim the foregoing as my invention I have signed my name in presence of two subscribing witnesses.

FRANK ALLEN.
